CLAIM

The ornamental design for a speed control handle for a pavement saw, as shown and described.

DESCRIPTION

FIG. 1 is a top, front and side perspective view of a speed control handle for a pavement saw showing my new design;

FIG. 2 is a top plan view thereof;

FIG. 3 is a front elevational view thereof, the rear view being a mirror image;

FIG. 4 is a side elevational view thereof; and,

FIG. 5 is a side elevational view of the opposite side of FIG. 4.

The slotted plate shown in broken lines in FIGS. 1-5 is for illustrative purposes only and forms no part of the claimed design.
